UNITED STATES PATENT OFFICE.

LOUIS HILL, OF AKRON, OHIO.

DIRECT THERMOSTATIC CUT-OFF MECHANISM.

Application filed November 14, 1923. Serial No. 674,629.

My invention relates to direct thermostatic gas cut-off mechanisms, my more particular purpose being to provide a very simple device of this kind, adapted for use upon ordinary gas burners, and in which a cut-off valve, through which gas is supplied to the burner, is operated by a controlling member heated by the burner and having the double function of a thermostatic bar and a closure spring; so that the flow of gas to the burner is cut off by the spring action of said controlling member, due to the change of form thereof, whenever by the accidental extinguishment of the burner flame, the said controlling member acquires a temperature low enough for this purpose.

Reference is made to the accompanying drawing forming a part of this specification, and in which like reference characters indicate like parts throughout all of the figures.

Figure 1 is a plan view of my device, showing one of the parts as partly broken away.

Figure 2 is a side elevation of the mechanism, certain parts being shown as broken away.

Figure 3 is a fragmentary view similar to the left hand portion of Figure 2, but showing the cut-off valve and movable parts immediately associated therewith, as they appear when the flow of gas as controlled by them is cut off.

A gas burner appears at 4, and connected with it is a mixing tube 5. Extending into the mixing tube, in the usual manner, for the purpose of delivering gas to the burner is a jet pipe 6.

A hand valve appears at 7, and may be used to control the supply of gas into the jet pipe. This hand valve is provided with a revoluble valve plug 8 and a handle 9 for use in turning the latter. The valve plug is provided with a passage 10, extending diametrically through it and adapted to be brought into and out of registry with the axial passage 11 of the jet pipe 6.

The jet pipe is provided with a valve plug 12, having a passage 13 extending diametrically through it, and so arranged that by rocking the valve plug 12 the passage 13 is brought into and out of registry with the passage 11.

Mounted rigidly upon the valve plug 12 is an arm 14, whereby it is actuated. The

valve plug 12 and parts immediately associated therewith constitute a cut-off valve. Located above the jet pipe 6 and the mixing tube 5 is a sliding bar 15, provided with a pivot pin 16, which extends loosely through the slot 17 so as to allow a little lost motion as between the arm 14 and the sliding rod 15. The sliding bar 15 extends through and is supported by a bearing 18, the latter being mounted upon and extending up from the mixing tube 5. The sliding bar carries a pair of stop pins 19 and 20, for limiting its travel, these pins being adapted to engage opposite sides of the bearing 18.

The sliding bar 15 is further provided with an upturned portion 21 serving as a thumb piece, to be engaged by the thumb of the operator and drawn to the left, into the position indicated for it in Figure 2, as hereinafter more fully described.

A controlling member 22, having a general arcuate form, is at one of its ends connected with the sliding bar 15, by a pivotal connection 23, as shown more particularly in Figure 1. The controlling member 22 is rigidly mounted upon the lug 24, or analogous support carried by the burner 4, and is held in position by a rivet 25 or equivalent fastening. By this arrangement the controlling member is supported rigidly at one of its ends, but is otherwise free except for its connection with the sliding bar. The controlling element 22 is essentially a thermostatic bar, having a function as a leaf spring, and so proportioned that, in acting as a leaf spring, it can readily turn the valve plug in a clockwise direction according to Figure 2, so as to shift the valve plug from the position indicated for it in Figure 2 to the one indicated for it in Figure 3, and thus cutting off the flow of gas through the jet pipe.

When no gas is flowing and the burner is cold, the valve plug 12 and movable parts immediately associated therewith occupy the positions indicated for them in Figure 3. When, however, the gas is flowing and the burner is heated and in action, the valve 12 and movable parts immediately associated therewith appear as indicated in Figure 2. Under the conditions just described the operator can grasp the handle 9, and by turning it can cut off the flow of gas through the valve 7, or regulate the flow, as described.

The operation of my device may be read-

ily understood from the foregoing description.

Suppose, at the start, that the burner is cold because no gas is flowing, and that the valve plug 12 and various movable parts immediately associated therewith appear in the positions indicated for them in Figure 3, and that the handle 9 of the valve 7 occupies the position indicated for it in this figure.

10 The operator places a thumb upon the thumb piece 21, and by drawing it to the left according to Figure 3, brings the sliding bar 15 and various parts actuating thereby into the positions indicated for them in Figure 2. This means that the valve plug 12 now permits the gas to flow through it to the burner.

The operator, still holding the thumb piece 21, now lights the gas at the burner. As the heat from the burner raises the temperature of the thermostatic bar 22, this bar ceases for the moment to act as a spring, but owing to its temporary distortion from the heat it tends to maintain the sliding bar 15 in its extreme position to the left as indicated in Figures 1 and 2.

The operator's thumb is now removed from the thumb piece 21. The valve plug 7 and various movable parts immediately associated with the valve plug continue to retain the positions just described for them, however, so long as the burner continues in action and even while the flow of gas is being controlled, at least within reasonable limits, through the agency of the valve 7. That is to say, the operator can grasp the handle 9 and move it back and forth within reasonable bounds in order to regulate and control the flow of gas to the burner, but 40 without causing the thermostatic bar to cut off the flow of gas through the other valve.

If, however, owing to any accidental cause, such as a sudden gust of wind, the burner flame is extinguished while the gas is left 45 still flowing to the burner, the cooling of the thermostatic bar causes the latter to move from the position indicated for it by full lines in Figure 1 to the position indicated for it by dotted lines in the said figure. The 50 thermostatic bar, owing to its change in form due to its cooling, now acts like a leaf spring under tension, and draws the sliding bar 15 to the right according to Figures 1 and 2, so as to rock the valve 12 in a clockwise direction according to Figure 2, and 55 cut off the flow of gas as above described.

The various parts above discussed are located closely together and so conveniently arranged that the operator can readily grasp 60 and actuate the handle 9 with one hand, say the left, and with the thumb of the same

hand can engage the thumb piece 21 and thus actuate the parts controllable thereby.

I do not limit myself to the precise mechanism shown, as variations may be made 65 therein without departing from my invention, the scope of which is commensurate with my claims.

Having thus described my invention, what I claim as new and desire to secure by Letters Patent is as follows:

1. In a device of the character described the combination, with a gas burner and a jet pipe for delivering gas into said gas burner, of a valve mounted upon said jet pipe for the purpose of automatically cutting off the flow of gas therethrough, an arm connected with said valve for the purpose of actuating the same, a sliding bar connected 75 with said arm for the purpose of actuating said arm, a bearing mounted upon said jet pipe and through which said sliding bar extends, and a controlling member connected with said sliding bar for the purpose of actuating the same, said controlling member being mounted adjacent said gas burner so as to be heated thereby while said gas burner is in action, said controlling member having the double function of a thermostatic 80 bar and a leaf spring, for the purpose of 85 actuating said sliding bar.

2. In a device of the character described the combination with a mixing tube and a burner, of a jet pipe leading into said mixing tube for the purpose of supplying gas through said mixing tube to said burner, a valve mounted upon said jet pipe for opening and closing the same, an arm connected with said valve for the purpose of actuating said valve in order to cut off the flow of 90 said gas to said mixing tube, a sliding bar connected with said arm for the purpose of actuating said arm, said sliding bar being provided with a thumb piece to enable said sliding bar to be moved by hand in order to cause said arm to open said valve, a bearing mounted upon said mixing tube and through which said sliding bar extends, a pair of stop pins carried by said sliding bar and located upon opposite sides of said bearing for limiting the travel of said sliding bar, and a controlling member connected with said sliding bar and located adjacent said burner in order to be heated thereby while said burner is in action, said controlling member having the double function of a thermostatic bar and a leaf spring.

Signed at Akron, in the county of Summit and State of Ohio, this 12th day of November 1923.

LOUIS HILL.
